UNITED STATES PATENT OFFICE.

J. ALBERT ESHLEMAN, OF PHILADELPHIA, PENNSYLVANIA.

IMPROVEMENT IN NECK-TIE HOLDERS.

Specification forming part of Letters Patent No. 56,196, dated July 10, 1866.

To all whom it may concern:

Be it known that I, J. A. ESHLEMAN, of Philadelphia, Pennsylvania, have invented an Improved Holder for Neck-Ties; and I do hereby declare the following to be a full, clear, and exact description of the same, reference being had to the accompanying drawings, and to the letters of reference marked thereon.

My invention consists of a plate attached to a neck-band and adapted for the reception and retention of a detachable tie, as fully described hereinafter, so that the said tie may be readily secured to or removed from the band, and so that when secured to the band the tie shall retain its proper form.

My invention further consists of devices, fully described hereinafter, for securing the band to the collar round which it is passed.

In order to enable others skilled in the art to make and use my invention, I will now proceed to describe the manner of constructing and using the same.

On reference to the accompanying drawings, which form a part of this specification, Figure 1 is a rear view of my improved holder for neck-ties; Fig. 2, a longitudinal section; Fig. 3, an exterior view, showing the tie secured to a band and to a collar; and Fig. 4, a vertical section on the line 1 2, Fig. 3.

A is a flat metal tube, at one end of which are two small projections, *i i*, and from the rear side of the socket projects a stud or button, *a*. B is a staple-like catch, consisting of a rod bent in the form of the letter **U**, and having in the outer edge of each arm a recess, *e*, Fig. 2. To one arm of the catch is secured one end of a cross-piece, C, the other end of which is almost in contact with the opposite arm, and in the end of each arm is an eye, *x*.

The catch B is attached to one end of a neck-band, X, by stitches passed through the eyes *x x*, and the socket A is secured to the opposite end of the band, the stud *a*, at the back of the socket, projecting through an opening in the said band. The strip Y, from which the bow or tie is to be formed, has an opening, *y*, near the middle, and through this opening is passed the stud *a*, after which the ends of the strip are tied into a bow in the usual manner.

The stud *a* is introduced into the usual button-hole of a "choker" collar, Z, at one side of

the button, which confines the same to the shirt. The band X is passed round the collar in the usual manner, and the end of the catch B is introduced into the socket A until the projections *i i* catch into the recesses *e e*.

When the tie has to be detached from the neck the wearer compresses the catch so as to remove the arms from contact with the projections *i i*, when the catch may be withdrawn from the socket. The socket may then be detached by turning it so that the stud *a* may be withdrawn from the button-hole.

It will be seen that the band may be readily secured to or detached from a collar without disturbing the tie, and that the soiling of the latter by repeatedly tying and untying it is avoided, while its proper form is preserved by the socket A, round which it is folded.

The tie may be readily detached from the band when it has to be replaced by another or when it has to be cleansed.

Although I prefer to use the socket A for maintaining the tie in its proper form, a flat plate may be used for that purpose, the plate being secured to the band and the strip Y being folded round it and tied, as before described, the ends of the band, in this instance, being secured together by any suitable means at the back of the collar.

Other devices may also be used in place of the stud *a* for preventing the band from slipping upward on the collar.

I claim as my invention and desire to secure by Letters Patent—

1. A plate secured to a neck-band and adapted for the reception and retention of a detachable tie, substantially as described.

2. The combination of the socket A or its equivalent and a stud, *a*, as and for the purpose specified.

3. The socket A, with its projections *i i*, and the spring-catch B, with its recesses *e e*, when constructed and adapted for attachment to each other and to a neck-band, substantially as set forth.

In testimony whereof I have signed my name to this specification in the presence of two subscribing witnesses.

J. ALBERT ESHLEMAN.
